R. E. MITTON
AEROPLANE CONTROL

1,470,998

Filed Aug. 14, 1922

Patented Oct. 16, 1923.

1,470,998

UNITED STATES PATENT OFFICE.

ROBERT ELVYN MITTON, OF SALT LAKE CITY, UTAH, ASSIGNOR TO MITTON-BRALEY AEROPLANE CONTROL COMPANY, OF SALT LAKE CITY, UTAH, A CORPORATION OF UTAH.

AEROPLANE CONTROL.

Application filed August 14, 1922. Serial No. 581,747.

To all whom it may concern:

Be it known that I, ROBERT ELVYN MITTON, a citizen of the United States, residing at Salt Lake City, in the county of Salt Lake 5 and State of Utah, have invented a new and useful Improvement in Aeroplane Controls, of which the following is a specification.

This invention relates to a certain new and useful controlling device for aeroplanes, 10 which consists of the novel arrangement of parts to be hereinafter described and claimed.

One object of this invention is to provide a control which will automatically maintain 15 the lateral and longitudinal stability of aeroplanes.

Another object of this invention is to provide a control which will instantly guide the machine in any direction, in a modified 20 manner, but when desirable, will make any correction necessary to maintain stability unaided by the pilot.

Another object of this invention is to provide a control with which it would be 25 difficult to place the aeroplane far from its natural flying attitude, thus doing away with the hazardous stunts.

Other objects and advantages will appear in the following specification.

30 Figure 1, is a side view of an aeroplane showing the invention in place with the control wires attached thereto.

Fig. 2, is a front view of Fig. 1.

35 Fig. 3 is a plan view of the invention. A denotes the frame, B the plane, C the right aileron, D the left aileron, E the elevators, F the pilot's seat.

The invention comprises the hand lever 1 supported by the swivel bearing 6, the 40 pendulum lever 3 having a universal support 7 and the connecting rod 2 one end of which is connected to the hand lever and the other end to the pendulum lever.

A pin 9 is placed through the lower end 45 of the handle lever 1 and journaled in the side of the bearing 6.

Shafts 10 extending from the sides of the universal support 6 the ends thereof resting in bearings 10' secured to the side 50 of the frame A. The pendulum lever 3 having a pin 11 therein the ends thereof journaled in the universal support 7. Secured to the swivel bearing 7 are shafts 7' the ends thereof passing through bearings 12 secured to the side of the frame A.

The shafts 7' passing out through the bearings 12 the ends thereof having horns 15 secured thereto to which one end of the elevator control wires 16 and 17 are attached.

The wire 16 is attached to the bottom horn and to the top king post of the elevator and is the wire for raising the elevator. Wire 17 is attached to the top horn and to the bottom king post of the elevator and is the wire for lowering the elevator.

Wires 18 and 19 fastened to the control 65 at 20 and running through pulleys 21 and 22 to the bottom king posts of the ailerons and the balance wire 23 fastened to the top king post of the right aileron and running 70 through pulleys 24 operates the ailerons when the control is moved to the right or left. The elevators are operated when the control is moved forward or backward.

Banking, turning, ascending and descending is accomplished in the following manner; moving the control handle 1 to the right moves pendulum 25 to the left raises 75 right aileron C and depress left aileron D, thus causing aeroplane to bank or lean to the 80 right.

Moving control handle 1 to the left moves pendulum 25 to the right, raises left aileron D and depress right aileron C, thus causing 85 the aeroplane to bank or lean to the left.

Pushing control lever 1 ahead moves pendulum to the rear, operates the horns 15 in such a way as to draw on the wire 17 to depress the elevator which raise the tail 90 and cause the aeroplane to descend.

Pulling control lever back moves pendulum to the front operates horns 15 in such a manner as to draw on wire 16 thus raising the elevators, depress the tail and causing the aeroplane to climb or ascend.

The foregoing movements are those made by the pilot's hand upon the control lever to guide the aeroplane up or down or tip it to the right or left. The following describes the movements of the plane away 95 from a level flying position and shows how the automatic corrections take place when the pendulum is left in different relative positions.

It will be understood that the rudder operated by the feet by means of the rudder bar 61 is used in conjunction with any of the above movements which involve a turning movement about the vertical axis.

After the study of the drawings of the in- 110

vention, it will be readily seen that since it is possible to operate the pendulum as well as the controlling surfaces, whenever a movement is made by the hands with the control lever, the pendulum can react these movements as far as the correction of any disturbance of the balance of the aeroplane is concerned. Thus if an upward current of air should unexpectedly raise the right wing out of level position it will be seen that the pendulum actuated by the force of gravity will not move with the ship but will remain straight downward. The ship tipping to the left would then automatically operate the hand lever to the right, since that it is obvious that the pendulum would then be in a position to the left, and in so doing would operate the ailerons to return the ship to a level position, then all controls would be neutralized.

It is stated above that the ship turns its control lever to the left under the aforesaid circumstances, this it does not really do, but, it accomplishes practically the same thing, because the ship turns about the longitudinal axis of the machine leaving the control lever and pendulum stationary, thereby operating the control more effectively and exactly than if the lever itself were moved to accomplish the same result. The operation of the ailerons by means of the control lever is fully explained in the paragraphs on operation. When the ship tips to the right or opposite to the above all movements and corrections for same are exactly opposite or vice-versa to the above.

Having disposed of the lateral oscillations of the aeroplane in flight in this manner. We will now take the longitudinal disturbances. Thus if an upward current of air should strike the tail of the machine it would throw it nose down or in a position to descend, which it would immediately do. In this case it would be seen that with the ship was tipping forward, it would leave the pendulum in exactly the same position as it would be if the lever was pulled back when the ship was level, or other words the pendulum would be hanging forward, the lever would be automatically thrown back, thus giving the proper correction, since this movement, as explained in the paragraphs on operation raises the elevators thereby depressing the tail to a level position, when all parts are neutralized because the pendulum is then in dead center.

If the ship should strike a current of air that would tip it backward or nose up the operation would be opposite from the above in every detail.

The single, lateral and longitudinal movements of the ship, taken separately having been described. I will give an explanation of the more complicated, combined, lateral and longitudinal movements and corrections.

Thus if an upward current of air should simultaneously raise the right wing and tail out of a level position, the ship tipping to the left and forward, would then automatically operate the lever to the right and backward, since it is obvious that the pendulum would then be in a position to the left and forward, and in so doing would operate the ailerons and elevators to return the ship to the level position, thus tipping lever backward and to the right rocking elevator horns on the end of the bearing shafts backward, thereby raising elevators, depressing left aileron and raising right aileron and causing the tail to be depressed, the right wing to be depressed and the left wing to be raised thereby returning the ship to a level position. Then all parts are neutralized because the pendulum would then be in dead center.

If an upper current of air should simultaneously raise the left wing and tail out of the level position, the control working through the principles explained above, would automatically move the lever to the left and backward, thus depressing the right aileron and raising the left aileron and the elevators causing the ship to return to a level position.

If a current of air should simultaneously raise the right wing and depress the tail out of level position the control would automatically move the lever to the right and forward, thus depressing the left aileron and raising the right aileron and depressing the elevators causing the ship to return to level.

If a current of air should simultaneously raise the left wing and depress the tail out of level position the control would automatically move the lever to the left and forward thus depressing the right aileron and raise the left aileron and depress the elevators, and causing the ship to return to a level position.

Having thus described my invention what I claim as new and desire to secure by Letters Patent, is;

1. In a control for aeroplanes of the character described, comprising a control lever, a pendulum lever and a connecting rod pivotably connecting said control lever and pendulum lever together, a universal support for said control lever, said control lever having a pin therein, said pin being journaled in said universal support, said universal support having shafts thereon, means for securing said shafts to the aeroplane, another universal support for said pendulum lever, said pendulum lever having a pin therein, said pin being journaled in said other universal support, said other universal support having shafts thereon passing through bearings secured to the side of the aeroplane the ends having horns secured thereto to which the wires of the elevator

are attached, means on said pendulum lever to secure the control wires to the ailerons.

2. In an aeroplane control of the character described, comprising a control lever, 5 a pendulum lever, and a connecting rod pivotably connecting said levers together, universal supports for each of said levers, said levers having pins therein, said pins being journaled in the sides of said universal supports, said universal supports having shafts projecting from the sides thereof, said shafts resting in bearings secured to the sides of the aeroplane frame, one of said shafts having horns secured to the ends 10 thereof, said horns for securing the ends of the wires for controlling the elevator and means for securing the wires to said pendu-

lum lever to control the operation of the ailerons.

3. In an aeroplane control of the character described, comprising a hand control lever, a connecting rod, a pendulum lever and a universal support for each of said levers, said connecting rod for connecting said hand control lever and pendulum lever 20 together, shafts on said universal supports resting in bearings secured to the sides of the aeroplane, horns on one set of said shafts having the elevator control wires attached thereto, aileron control wires attached to 25 said pendulum lever and means for securing said wires to said pendulum lever.

In witness whereof I affix my signature.
ROBERT ELVYN MITTON.
